DESIGN FOR A STEERING WHEEL FOR MOTOR VEHICLES OR THE LIKE

Daniel S. Hoover, Mansfield, Ohio

Application August 1, 1938, Serial No. 79,017

Term of patent 7 years

To all whom it may concern:

Be it known that I, Daniel S. Hoover, a citizen of the United States, residing in Mansfield, in the county of Richland and State of Ohio, have invented a new, original, and ornamental Design for a Steering Wheel for Motor Vehicles, or the like, of which the following is a specification, reference being had to the accompanying drawing, forming part thereof, in which:

Figure 1 is a top plan view of the steering wheel for a motor vehicle;

Figure 2 is a central transverse sectional view of the steering wheel; and

Figure 3 is a transverse sectional view taken on line 3—3 of Figure 1.

I claim:

The ornamental design for a steering wheel for motor vehicles or the like, as shown.

DANIEL S. HOOVER.
